The ornamental design for an end piece for a roll dispenser, as shown and described.

DESCRIPTION

FIG. 1 is a front perspective view of an end piece for roll dispenser, showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is bottom plan view thereof;

FIG. 9 is a front perspective view thereof, in use condition, with one additional end piece for roll dispenser to other end; and,

FIG. 10 is a second front perspective view thereof, in an alternate usage conditions.

The broken lines shown in FIGS. 9-10 illustrate environmental subject matter only and form no part of the claimed design.
